FILLING MACHINE

John M. Hothersall, Brooklyn, N. Y., and William Pechy, Elizabeth, N. J., assignors to American Can Company, New York, N. Y., a corporation of New Jersey

Application October 29, 1937, Serial No. 171,786

15 Claims. (Cl. 226—97)

The present invention relates to a machine for filling liquids into containers or cans and has particular reference to improved devices for measuring out a predetermined volume of liquid and for filling this measured liquid into a can 5 having an attached closure element, the while holding the closure element in open and non-interfering position.

An object of the invention is the provision of 10 a machine for filling a measured charge of liquid, such as for example milk, into a fibre can of the type having a hinged closure element or flap which is preferably attached to a wall containing a filling and dispensing opening and 15 which is adapted to close and seal the opening, after the can is filled.

Another object is the provision of a filling 20 machine of this character wherein a plurality of cans may be introduced into and passed through the machine in a continuous procession, each can being filled in its proper order with a predetermined charge of liquid and discharged after filling without interruption to the filling operation.

25 Another object is the provision in such a filling machine of devices for holding the can closure element in a position which will uncover the filling opening in the can and at the same time be out of the way while the can is being 30 filled.

Another object is the provision in a machine 35 of this character of improved liquid measuring and can filling instrumentalities which are designed to segregate predetermined charges of liquid from a main source of supply such as a reservoir, and to fill these measured charges into cans with a minimum of agitation.

Numerous other objects and advantages of the 40 invention will be apparent as it is better understood from the following description, which, taken in connection with the accompanying drawings, discloses a preferred embodiment thereof.

Referring to the drawings:

45 Figure 1 is a side elevation of a filling machine embodying the instant invention, parts of the machine being broken away and parts being shown in section;

50 Fig. 2 is a top plan view of the machine, with parts broken away and parts in section;

55 Fig. 3 is an enlarged sectional detail taken substantially along the line 3—3 in Fig. 2, with parts broken away, the view also showing the upper end of a can to be filled;

Figs. 4 and 5 are enlarged fragmentary sections taken substantially along the respective lines 4—4, 5—5 in Fig. 2 both views showing substantially the same parts but with certain moving parts in different positions, Fig. 5 in addition 5 also showing a can in section as being filled;

Fig. 6 is a sectional detail taken substantially along the horizontal line 6—6 in Fig. 5;

Figs. 7 and 8 are views similar to Figs. 4 and 10 5 showing the machine parts and a can in different positions, the views being taken substantially along the respective lines 7—7, 8—8 in Fig. 2;

Fig. 9 is an enlarged fragmentary section taken substantially along the vertical line 9—9 in Fig. 15 1; and

Fig. 10 is a horizontal section taken substantially along the broken line 10—10 in Fig. 9.

An exemplary form of can which is adapted to be filled in the machine illustrated in the 20 drawings is fully disclosed in United States Patent Number 2,085,979, issued to John M. Hothersall on July 6, 1937. Such a can is herein indicated by the letter b. The can is preferably made of fibre and is provided with fibre 25 top and bottom end members. The top end member is formed with a filling and dispensing opening c which is disposed at one corner of the can. This opening is adapted to be subsequently closed and sealed, after the can is filled, by a 30 flap or closure element d which is hingedly secured to the top end member. The closure element is provided with a plug section e formed to fit into and fill the opening c when the closure element is in can closing position.

35 As a preferred embodiment of the present invention the drawings disclose a multiple head filling machine which is adapted to fill the cans b with milk as they move along in a continuous 40 procession. The milk to be filled into the cans a is retained in a rotatable reservoir or tank A (Figs. 1, 2, 4, 5, 7 and 8) which is provided with a plurality of depending filling heads B (see also Fig. 3). Each filling head contains a measuring element C which segregates from the milk in the 45 tank a predetermined charge of the milk and holds it confined within the filling head for delivery into a can b.

The cans to be filled are fed into the machine 50 from any suitable source of supply and are advanced by a feeding device D (Figs. 1 and 2) to meet the charged filling heads B. The advancing cans are in a vertical position with their closure elements d held open so as to uncover

their filling openings *c*. The closure elements *d* are held in this opened position by suitable instrumentalities throughout the entire passage of the can through the machine.

5 A transfer device *E* (Figs. 1 and 2) shifts the fed cans individually from the feeding device *D* into a can carrier mechanism *F* where the cans are received on lifter pads *G* disposed directly beneath the charged filling heads *B*. The can carrier rotates with the tank *A* and hence carries the cans in a circular path of travel while retaining them in vertical alignment with the filling heads. During this travel the lifter pads *G* raise the cans into closer association with the 10 filling heads and the segregated charges of milk 15 are delivered into the cans.

Near the end of the circular path of travel of the cans the lifter pads *G* return the filled cans to their original level in the can carrier 20 mechanism *F* and they are removed from the machine for sealing. Removal of the filled cans is effected by suitable discharge instrumentalities *H* (Figs. 1 and 2).

The rotatable milk reservoir or tank *A* is provided with a cover *21* (Fig. 1) and the tank is mounted on top of a vertical spindle *22* (see also Fig. 9). The lower end of the spindle is shouldered as at *23* and is carried in a bearing *24* formed in a machine base member *25* and also 30 in a bearing *26* which is formed in a short column *27* supported on the base member.

The spindle *22* is continuously rotated by a ring gear *31* (see also Fig. 10) which is keyed to the spindle between the spindle shoulder *23* 35 and the column bearing *26*. The ring gear meshes with one of a pair of meshing idler gears *32* mounted on shouldered studs *33* carried in a gear housing *34* bolted on the machine base member *25*. The other idler gear *32* meshes with a 40 spur gear *35* carried on the lower end of a vertical shaft *36* journaled in a bearing *37* formed in the gear housing.

Gear *35* is driven by a pinion *38* mounted on a vertical shaft *39* carried in bearings *41* formed 45 in the gear housing *34*. Shaft *39* also carries a bevel gear *42* which meshes with a bevel pinion *43* mounted on one end of a main driving shaft *44*. The driving shaft is journaled in a bearing *45* 50 formed in a bracket *46* of the gear housing *34* and also in a bearing *47* formed in a machine frame *48* mounted on the machine base member *25*. This driving shaft is rotated by any suitable means operating in time with the other moving parts of the machine and thus through 55 the gear train just described rotates the spindle and the milk tank *A* mounted thereon.

The milk adapted to be filled into the cans *b* is received from any suitable source of supply 60 and is fed into the tank by way of an inlet pipe *51* (Fig. 1). The inlet pipe extends down through the middle of the tank cover *21* and terminates inside the tank. The lower end of the pipe is closed off and an adjacent port *52* is provided 65 in the side of the pipe near its closed end for delivering the milk into the tank.

The level of the milk in the tank *A* is preferably maintained at a predetermined height by a suitable sleeve valve *55* which surrounds the 70 lower end of the inlet pipe *51*. The valve is attached to a float *56* supported by the milk in the tank. Thus as the milk level rises and falls the float moves the sleeve valve and thereby covers or uncovers the port *52* for regulating 75 the flow of milk into the tank. A screen *57* is

provided on the float to screen the milk as it enters the tank.

The can filling heads *B* hereinbefore mentioned are formed on the bottom of the milk tank *A* and are arranged in a circle and in spaced relation adjacent the periphery of the tank. Each filling head includes a tubular member *61* (Figs. 4, 5, 7 and 8) which is preferably formed integrally with the bottom of the tank *A*. The lower end of the member is closed by a funnel shaped cap *62* having a vertical rim *63* which fits inside of the tubular member *61*. The cap is also provided with a cylindrical nozzle *64* having a milk delivery port or slot *65* formed in its side wall adjacent its lower end. 15

Delivery of milk from the nozzles *64* is controlled by nozzle valve mechanism and this mechanism for each head includes a valve plunger *68* normally disposed within the nozzle as shown in Fig. 4. The valve plunger is formed on the 20 lower end of a vertically disposed valve rod or stem *69* which extends up through an opening *71* in the milk tank cover *21* and terminates outside of the tank.

The upper end of the valve rod is secured to 25 an arm *72* which connects with a vertical push rod *73* (see also Fig. 1) disposed alongside the tank *A*. The push rod is carried in suitable bores formed in a pair of spaced annular upper and lower flanges *74* formed on the outer side 30 wall of the tank. The lower end of the push rod *73* engages against an adjustable setscrew *76* which is carried in a valve actuating member *77*.

The valve actuating member is a vertically 35 movable elongated tubular casting which slides along and is supported on a long screw *78* which is threaded into the lower flange *74* of the tank *A*. The valve member is guided in its vertical movement on the screw *78* by a parallel pin *79* 40 which is also secured in the lower flange *74* of the tank.

The valve mechanism is operated by the valve actuating member *77* which is adapted to be raised vertically by engagement with a can *b* 45 to be filled. For this purpose the lower end of the tubular part of the valve actuating member is formed with a depending foot *81* which is disposed adjacent the nozzle *64*. When not engaged by a can and just prior to the normal time 50 for such engagement the valve actuating member is held in a slightly elevated position by a cam roller *82* which is carried by the member adjacent its upper end. This elevated position, however, is not sufficient to open the nozzle *64*. 55

The cam roller *82* when holding the valve actuating member slightly elevated rolls over a stationary segment cam *83* disposed adjacent the periphery of the tank *A*. One end of the cam segment is carried on an upright *84* (Fig. 1) 60 supported on a bracket *85* which is bolted on the machine frame *48*. The other end of the cam is carried on an arm *86* which extends inwardly from and is clamped on a column *87* supported on the machine base member *25*. 65

As the rotating tank *A* carries a valve actuating member *77* beyond the end of the cam *83* the roller *82* rides off the cam into space. The valve actuating member thereupon drops to its lowermost position where it is supported on the head 70 of the screw *78* as shown in Fig. 7. The parts are in this position when a can *b* comes under the associated filling head *B* as will be hereinafter explained but first consideration will be given to the milk measuring units. 75

Before the nozzle valve is opened, a predetermined charge of the milk in the tank A is measured out by the measuring element C located in the filling head. The measuring element 5 rounds the nozzle valve rod 69 and is shaped like a bottle without any bottom, having a large lower portion 91 which merges (Figs. 4, 5, 7 and 8) into a smaller upper or neck portion 92. Both ends are open.

10 The lower enlarged portion of the measuring element is disposed within the filling head member 61 and is provided with outwardly extending protuberances 93 which engage the inner wall 15 of the filling head. These centralize and guide it for vertical movement within the filling head. In lowered position of the measuring element its lower end fits within the vertical rim 63 of the filling head cap 62 (Figs. 5 and 7). The cooperating edges of the rim and the measuring element 20 are beveled to facilitate this fitting engagement.

The upper or neck portion 92 of the measuring element extends up through the milk in the tank A and projects through the tank cover opening 25 71. A dust cap 94 carried on the nozzle valve rod 69 prevents the entrance of foreign matter into the milk through the open upper end of the measuring element. Above the milk level, the neck 92 is provided with a pair of liquid return 30 outlets or slots 96 which are disposed adjacent and just beneath a splash guard 97 carried on the neck.

Outside of and above the tank A, the neck portion of the measuring element carries an inverted cup shaped shield 98 for protecting the cover opening 71 against entrance of foreign matter into the milk. The shield also serves as a support for the upper end of the measuring 35 element.

40 Shield 98 is secured to the upper end of a shouldered rod 101 (see also Fig. 1) carried in bores 102 provided in the upper and lower flanges 14 of the tank A. The rod is threaded into a block 104 which is formed with side wings 105 45 which rest against the outside of the tank. These wings prevent turning of the block relative to the tank.

The block 104 carries a cam roller 107 which 50 during a portion of the rotation of the tank A rolls along a stationary segment cam 108. This cam is located just above the cam 83 and is substantially parallel and coextensive with it. The ends of the cam 108 are mounted in the same manner as the cam 83 one end being carried on the upright 85 while the opposite end is supported on the column 87.

As a filling head B comes adjacent the cam 108 55 in its travel around the center of the machine the cam roller 107 rides up on the cam and the block 104 with its rod 101 is thereby lifted. This action raises the measuring element within the filling head and withdraws its lower end from the rim 63 of the filling head cap 62. Milk in 60 the tank A and particularly in the filling head member 61 thereupon flows into the measuring element through its open bottom end, the milk level therein rising into the neck portion of the measuring element to the level of the milk in 65 the tank. This level it will be remembered is below the bottom of the slots 96 in the neck of the measuring element.

The distance the measuring element rises 70 above the rim 63 of the filling head cap 62 may be 75 adjusted so as to obtain slower or faster filling

action. This adjustment is effected by turning the rod 101 in its block 104, a square head 109 (Fig. 4) being formed on the lower end of the rod to permit easy manipulation by a wrench.

As the rotating tank A carries the filling head 5 along the entire length of the cam 108, the roller 107 leaving the cam end rides off into space and the measuring element C thereupon falls down within the filling head. The lower end of the falling measuring element re-seats itself 10 within the rim 63 of the filling head cap 62 and is brought to rest in its predetermined lowermost position by engaging an adjustable stop screw 15 111 (Fig. 7).

The stop screw 111 for each head is carried in a 20 lug 112 formed on the upper flange 74 of the tank A. A stop lug 113 is an integral part of the shield 98 and projects outside of the tank wall where it can engage against the stop screw 111 as already described. By adjusting the lowermost position of the measuring element as determined by the position of the top of the stop screw, the volume of the measuring element may be readily and accurately controlled so that a 25 specific charge of milk may be confined within it. This will become more apparent as the description proceeds.

Re-seating of the measuring element in its lowered position cuts off communication between 30 the tank and the inside of the element and thus traps a quantity of milk in the measuring element. This re-seating also forces a portion of the trapped milk up into the neck and up beyond the slots 96. Hence overflow or excess milk 35 gushes out through the slots (Fig. 4) and is directed back into the tank by the splash guard 97.

When this overflow action ceases, the milk level in the measuring element comes to rest at the bottoms of the slots 96. The bottoms of these 40 slots are beveled as shown to provide a sharp cut-off. A predetermined charge of milk thus remains trapped in the measuring element. It is this measured charge of milk which goes into a can b by way of the nozzle 64. It is at this time 45 in the cycle of movement of the filling head B under consideration that a can b is introduced into the machine by the can feeding device D and this phase of the can movement will now be considered.

The can feeding device D (Figs. 1 and 2) 50 comprises a continuously rotating feed-in turret 121 which is mounted on a vertical shaft 122 carried in suitable bearings formed in the machine frame 48 and also in the bracket 85. Shaft 122 is rotated by any suitable means operating in time 55 with the other moving parts of the machine.

The feed-in turret 121 is provided with spaced 60 pockets 126 which receive and move the cans in timed relation toward the charged filling heads B. During this feeding movement the cans are supported on a horizontal table portion 127 of the machine frame 48. The moving cans are retained in the turret pockets 126 by a curved guide rail 128 which is secured to the top of the table 65 portion 127. A similar guide rail 129 is parallel to the rail 128 but is above the cans where it extends along the path of travel of the open closure elements or flaps d of the moving cans. This upper guide rail keeps the flaps in opened position. 70 Upper guide rail 129 is bolted to the bracket 85.

The guide rails 128, 129 terminate adjacent the can transfer mechanism E (Figs. 1 and 2) which operates at the proper time to remove the cans 75

from the feed-in turret 121 and to place them in the can carrier mechanism F. This can transfer is effected by a pair of upper and lower arms 132, 133 which are disposed respectively above and below the turret 121.

Upper arm 132 is mounted on a short pin 134 held in the bracket 85. The lower arm 133 is mounted on a shaft 135 which is on the same axial center as the pin 134. Shaft 135 is carried 10 in a bearing formed in the table portion 127 of the frame 48. This shaft is rocked by any suitable means operating in time with the other moving parts of the machine. The arms are connected by a tie rod 136 and hence move in unison 15 when the shaft 135 is rocked.

When a fed can b reaches the ends of the guide rails 128, 129 the transfer arms 132, 133 move in behind the can and push it out of its rotating turret pocket 126. As the can passes the exit 20 ends of the guide rails 128, 129 it comes into the entrance end of a similar guide rail 138. Rail 138 is mounted on uprights 139 adjacent to and just outside of the can carrier mechanism F. These three guide rails cooperate in guiding the 25 can while holding its closure element d open during the transfer.

The filling head B which contains the measured charge of milk which is to go into that particular can now passes in position to receive the can. 30 The foot 81 on the valve actuating member 71 (Fig. 4) slips in front of the open can closure element d as the element leaves the end of the guide rail 129 (see Fig. 1) and continues to hold the can closure element open. The foot 81 remains in 35 such position and continues to hold the closure element open during travel of the can in the can carrier F.

A can b thus transferred into the can carrier mechanism F is received in one of a plurality 40 of spaced pockets 142 of a carrier turret 143 (Figs. 1, 2 and 9). This turret is formed on the spindle 22 below the milk tank A and hence is rotated with the tank. The turret pockets are 45 in vertical alignment with the filling heads B and a can placed into one of these pockets is in such a position that its filling opening c is in direct vertical alignment with the filling head nozzle 64.

While in the can carrier mechanism F the 50 can b is supported on the lifter pad G associated with that filling head. There is one of these pads located under each of the pockets 142 of the turret 143. Each lifter pad is formed on top of a stem 145 carried in a wheel 146 formed integrally with the ring gear 31 on the spindle 22. At its lower end each stem 145 carries a cam roller 147 which during a portion of the rotation of the spindle passes over a stationary segment cam 148. The cam is bolted to a bracket 149 formed integrally with the short column 27.

As soon as the moving can is clear of the transfer mechanism E it is lifted vertically in its turret pocket 142 by the raising of its lifter pad G. 65 This is effected by the cam roller 147 riding up on the cam 148. The rising can envelopes the lower end of the filling head nozzle 64, the latter entering the can through its filling opening c as shown in Fig. 5. In this elevated position of the 70 can the milk delivery slot 65 of the nozzle is just inside the can and is just under its top end member.

During this lifting action of the can its top end member engages against the bottom of the foot 75 81 of the nozzle valve actuating mechanism and

raises the parts connecting with the valve plunger 68. The closure element d still resting against the side of the foot 81 slides up alongside.

The plunger 68 is thereby withdrawn from the nozzle and the segregated charge of milk confined in the measuring element C flows out through the nozzle slot 65 and into the can. The slot 65 is so formed as to direct the stream of milk outwardly in a fan shape (Fig. 6) and against the sides of the can. This overcomes 10 any tendency of the milk to foam. The measured charge of milk is just sufficient to properly fill the can.

It takes some time to complete the filling of the can and the entire action takes place while 15 the can moves along its circular path of travel around the spindle 22 as a center. This filling operation in fact consumes the greater part of the machine cycle. The closure element d of the can remains in contact with the foot 81 so that it is 20 held away from the nozzle. The can also remains in its elevated position on the lifter pad G, the latter being held up by the cam 148.

By the time the can is completely filled, i. e., when the contents of the measuring element have 25 been fully delivered into the can, the can is near the end of its circular path of travel. The filled can is now lowered to its original position. This withdraws the nozzle from the can filling opening c (see Fig. 7).

Lowering of the filled can is effected by the lifter pad cam roller 147 riding off the end of the cam 148. The foot 81 of the nozzle valve actuating mechanism still holding the can closure element open, follows the can in its descent and the 35 valve plunger 68 re-seats into the nozzle 64. This closes the nozzle. The valve rod 69 during this descent is maintained in vertical alignment by an enlarged portion 150 which slides on the inside of the neck 92 of the measuring element c.

Following this can descent in the cycle of the 40 machine, the cam roller 82 passes onto the cam 83 and the cam action thereupon raises the foot 81 slightly above the top end member of the can so that it clears the can top (see Fig. 8). This 45 raising of the foot 81 is not enough to open the nozzle 64 nor to disengage the foot from its action in holding the can closure element open. Simultaneously the cam roller 107 again engages the cam 108 and this cooperation raises the measuring element C within its filling head B (see Fig. 8) so that a succeeding charge of milk for a 50 subsequent can flows into the element. It is while the cams 83, 108 are thus holding their co-operating machine parts that the filled can is 55 discharged from the can carrier mechanism F by the instrumentalities H.

The can discharge instrumentalities H (Figs. 1 and 2) include a star wheel 152 which is mounted on the constantly rotating vertical shaft 36 of 60 the spindle driving mechanism. The star wheel is formed with spaced pockets 153 and also carries prongs 154. Further, the star wheel is partially surrounded by a concentric guide rail 155 which is bolted to the table portion 127 of the 65 machine frame 48. The inner end of the guide rail extends across the path of travel of the filled cans in the can carrier turret 143.

As a filled can in the can carrier turret 143 comes abreast of the star wheel 152, a prong 154 70 of the wheel engages behind the can and sweeps it against and along the inner end of the guide rail 155. This removes the can from its turret pocket 142 and from its lifter pad G and inserts it into a pocket 153 of the star wheel. The can 75

during this transfer passes onto the table portion 127 of the machine frame. The guide rail holds the can within the rotating star wheel while it is moved across the table 127 to any suitable place 5 of discharge.

It is thought that the invention and many of its attendant advantages will be understood from the foregoing description, and it will be apparent that various changes may be made in the form, 10 construction and arrangement of the parts without departing from the spirit and scope of the invention or sacrificing all of its material advantages, the form hereinbefore described being merely a preferred embodiment thereof.

15 We claim:

1. In a machine for filling liquid into containers, the combination of a filling head for holding a filling liquid, a liquid measuring element located in said filling head and movable into and 20 out of sealing engagement therewith, means for moving said measuring element away from and out of sealing engagement with said head to receive an amount of liquid therefrom in excess of a predetermined filling charge, and then for moving 25 said element towards said head to segregate said received liquid within said element while returning excess liquid to said head, said means being further operative to move said measuring element into sealing engagement with said head 30 to confine therebetween said predetermined filling charge after excess liquid has been returned to said head, preparatory to filling said charge into a said container.

2. In a machine for filling liquid into containers, the combination of a rotary filling head for holding a filling liquid, means for rotating said head, a liquid measuring element located in said filling head and movable into and out of sealing engagement therewith, means actuated by the 40 rotation of said filling head for moving said measuring element away from and out of sealing engagement with said head to receive an amount of liquid therefrom in excess of a predetermined filling charge and then for moving said element 45 towards said head to segregate said received liquid within said element while returning excess liquid to said head, said means being further operative to move said measuring element into sealing engagement with said head to confine there- 50 between said predetermined filling charge after excess liquid has been returned to said head, preparatory to filling said charge into a said container.

3. In a machine for filling liquid into containers, the combination of a rotary filling head for holding a filling liquid, means for rotating said head, a liquid measuring element located in said filling head and movable into and out of sealing engagement therewith, means actuated by the 60 rotation of said filling head for moving said measuring element away from and out of sealing engagement with said head to receive an amount of liquid therefrom in excess of a predetermined filling charge and then for moving said element 65 towards said head to segregate said received liquid within said element while returning excess liquid to said head, said means being further operative to move said measuring element into sealing engagement with said head to confine there- 70 between said predetermined filling charge after excess liquid has been returned to said head, preparatory to filling said charge into a said container, means for vertically moving a said container, and means engageable with and actuated

by said moving container for filling said measured charge of liquid thereinto.

4. In a machine for filling liquid into containers, the combination of a filling head for holding a filling liquid, a liquid measuring element located in said filling head and movable into and out of sealing engagement therewith, means for moving said measuring element away from and out of sealing engagement with said head to receive an amount of liquid therefrom in excess of a predetermined filling charge, and then for moving said element towards said head to segregate said received liquid within said element while returning excess liquid to said head, said means being further operative to move said measuring element into sealing engagement with said head to confine therebetween said predetermined filling charge after excess liquid has been returned to said head, preparatory to filling said charge into a said container, and means for regulating the non-sealing position of said measuring element relative to said filling head to control the rate of flow of liquid flowing thereinto from said head.

5. In a machine for filling liquid into containers, the combination of a rotary filling head for holding a filling liquid, means for rotating said head, a liquid measuring element located in said filling head and movable into and out of sealing engagement therewith, means actuated by the rotation of said filling head for moving said measuring element away from and out of sealing engagement with said head to receive an amount of liquid therefrom in excess of a predetermined filling charge and then for moving said element towards said head to segregate said received liquid within said element while returning excess liquid to said head, said means being further operative to move said measuring element into sealing engagement with said head to confine therebetween said predetermined filling charge after excess liquid has been returned to said head, preparatory to filling said charge into a said container, and adjustable stop devices for regulating the measuring position of said element relative to said filling head to control the amount of said predetermined measured filling charge.

6. In a machine for filling liquid into containers, the combination of a rotary filling head for holding a filling liquid, means for rotating said head, a liquid measuring element located in said filling head and movable into and out of sealing engagement therewith, means actuated by the rotation of said filling head for moving said measuring element away from and out of sealing engagement with said head to receive an amount of liquid therefrom in excess of a predetermined filling charge and then for moving said element towards said head to segregate said received liquid within said element while returning excess liquid to said head, said means being further operative to move said measuring element into sealing engagement with said head to confine therebetween said predetermined filling charge after excess liquid has been returned to said head, preparatory to filling said charge into a said container, and a nozzle on said filling head for delivering the predetermined measured charge of liquid into a container to be filled, said nozzle having a laterally disposed slotted delivery opening adapted to direct the liquid in a fan-shaped flat spray against the side wall of the container for preventing undue agitation of the liquid during the filling operation.

7. In a machine for filling liquid into containers, the combination of a rotary filling head for holding a filling liquid, means for rotating said head, a liquid measuring element located in 5 said filling head and movable into and out of sealing engagement therewith, means actuated by the rotation of said filling head for moving said measuring element away from and out of sealing engagement with said head to receive an 10 amount of liquid therefrom in excess of a predetermined filling charge and then for moving said element towards said head to segregate said received liquid within said element while returning excess liquid to said head, said means being 15 further operative to move said measuring element into sealing engagement with said head to confine therebetween said predetermined filling charge after excess liquid has been returned to said head, preparatory to filling said charge into 20 a said container, a nozzle on said filling head for delivering the predetermined measured charge of liquid from said element into a container to be filled, and valve means actuated by vertical movement of an empty container for opening 25 said nozzle.
8. In a machine for filling liquid into containers, the combination of a rotary filling head for holding a filling liquid, means for rotating said head, a liquid measuring element located in 30 said filling head and movable into and out of sealing engagement therewith, means actuated by the rotation of said filling head for moving said measuring element away from and out of sealing engagement with said head to receive an 35 amount of liquid therefrom in excess of a predetermined filling charge and then for moving said element towards said head to segregate said received liquid within said element while returning excess liquid to said head, said means being 40 further operative to move said measuring element into sealing engagement with said head to confine therebetween said predetermined filling charge after excess liquid has been returned to said head, preparatory to filling said charge into 45 a said container, a nozzle on said filling head for delivering the predetermined measured charge of liquid from said element into a container to be filled, valve means in said filling head for opening and closing said nozzle, and devices operable by vertical movement of said container for 50 actuating said valve means.
9. In a machine for filling liquid into containers, the combination of a rotary filling head for holding a filling liquid, means for rotating 55 said head, a liquid measuring element disposed in said filling head and having a liquid inlet opening and a liquid return outlet, and means actuated by the rotation of said filling head for successively moving said measuring element into 60 and out of engagement with said head for respectively sealing and opening said liquid inlet, said measuring element when out of engagement with said head receiving liquid therefrom through said inlet opening and when in sealing 65 engagement with said head first segregating a quantity of liquid in excess of a predetermined filling charge and then confining said charge within the element after having returned excess liquid to said filling head through said return outlet.
10. In a machine for filling liquid into containers, the combination of a rotary filling head for holding a filling liquid, means for rotating said head, a liquid measuring element disposed in 75 said filling head and having a liquid inlet open-

ing in the bottom of said element and a liquid return outlet in the upper portion thereof, and means actuated by the rotation of said filling head for successively moving said measuring element on its vertical axis into and out of engagement with said head for respectively sealing and opening said liquid inlet, said measuring element when out of engagement with said head, receiving liquid therefrom through said inlet opening, and when in sealing engagement with said head, first segregating a quantity of liquid in excess of a predetermined filling charge and then confining said charge within the element after having returned excess liquid to said filling head through said return outlet. 15

11. In a machine for filling liquid into containers, the combination of a rotary filling head for holding a filling liquid, means for rotating said head, a bottle shaped liquid measuring element disposed in said filling head and having an enlarged body portion open at one end to provide a liquid inlet opening and a restricted neck portion provided with a liquid outlet opening, and means actuated by the rotation of said filling head for successively moving said measuring element into 20 and out of engagement with said head for respectively sealing and opening said liquid inlet, said measuring element when out of engagement with said head, receiving liquid therefrom through said enlarged inlet opening and when in sealing engagement with said head first isolating a quantity of liquid in excess of a predetermined filling charge and then confining said charge within the element after having forced liquid into 25 said restricted neck portion of said element to return excess liquid to said filling head through said liquid outlet opening.

12. In a machine for filling liquids into containers, the combination of a filling head for holding a liquid, a measuring element in said filling head, means for moving said measuring element into and out of sealing engagement with said filling head for successively measuring predetermined charges of liquid, means for advancing a container into filling position relative to 40 said filling head, means for elevating said container relative to said filling head, and means actuated by the elevating of said container for filling a said measured charge of liquid thereinto 45 while said measuring element is in sealing engagement with said filling head.

13. In a machine for filling liquids into containers having filling openings and attached closure elements, the combination of a filling head for holding a liquid, a measuring element in said filling head for measuring a predetermined charge of liquid, valve means associated with said filling head for delivering said charge of liquid into a container, valve actuating devices operable by the container, a lifter pad for raising 55 said container into association with said filling head, means for advancing and placing said container onto said lifter pad, and devices for holding the container closure element open while being advanced and placed on said lifter pad. 60

14. In a machine for filling liquids into containers having attached closure elements, the combination of a filling head for holding a liquid, a measuring element in said filling head for measuring a predetermined charge of liquid, 70 means for advancing a container into filling position relative to said filling head, means for elevating said container relative to the filling head, means actuated by the elevation of said container for filling said measured charge of liquid there- 75

into, and devices for holding the container closure element open while being advanced and while being filled.

15. In a machine for filling liquids into containers having filling openings and attached closure elements, the combination of a filling head for holding a liquid, a measuring element in said filling head for measuring a predetermined charge of liquid, valve means associated with said filling head for delivering said charge of liquid into a container, valve actuating devices operable by the container, a lifter pad for raising said container into association with said filling head,

means for advancing and placing said container onto said lifter pad, devices for holding the container closure element open while being advanced and placed on said lifter pad, and a member co-operating with said valve actuating means and 5 movable with said container for holding the container closure element open and out of the way of said filling head while the container is moved into and out of filling position and also during the filling of the container. 10
